INVENTOR

I. A. Oliver

UNITED STATES PATENT OFFICE.

IMMANUEL ALVIN OLIVER, OF SANTA CLARA, CALIFORNIA.

DEEP-WELL TURBINE PUMP.

Application filed July 14, 1923. Serial No. 651,605.

To all whom it may concern:

Be it known that I, IMMANUEL ALVIN OLIVER, a citizen of the United States, residing at Santa Clara, in the county of 5 Santa Clara and in the State of California, have invented certain new and useful Improvements in Deep-Well Turbine Pumps, of which the following is a specification.

My invention relates to new and useful 10 improvements in deep well turbine pumps and more particularly to a new form of impeller and the turbine casing bowl in which it operates.

Deep well turbine pumps are, commonly, 15 of either the screw propeller or the in- closed impeller types, both having operating characteristics suitable for certain kinds of work. The screw propeller, while being capable of delivering large capacities in pro- 20 portion to size, is efficient only at low heads and favorable pumping conditions. The in- closed impeller, most commonly used, though being capable of high heads and 25 good efficiencies, has the disadvantage of limited capacities and of producing exces- sive friction at high speeds, and the suc- 30 tion necks or clearance rings wear out very rapidly in gritty water, allowing leakage and by-pass losses.

It is an object of this improvement to de- 35 vice a deep well pump combining the good features of the screw propeller and the in- closed form of impeller, by providing an 40 impeller of the open type, without shroud or clearance rings, and of conical form, 45 having helically curved vanes formed on a conical central hub and having their lower 50 ends also formed to the outlines of a cone, the impeller operating in a turbine bowl 55 having an annular chambered portion with wall sides disposed at the same angle as the impeller vane lower ends, providing a seat 60 therefor and forming a close running fit or clearance ring preventing leakage and by- 65 pass. By virtue of the conical form of the impeller channels, being of a larger diameter 70 at the discharge end, the full effect of the centrifugal force of the water is utilized, 75 while at the same time the open type of im- 80 peller reduces the hydraulic friction to a 85 minimum, and produces larger capacities 90 per given size.

It is a further object to provide warped 95 or twisted impeller vanes disposed at right 100 angles to the conical surface and pitching 105 upward with the proper angle to elevate the

water with a minimum of shock and hy- 60draulic losses. It is a still further object to provide a turbine bowl adapted to incase 65 the impeller, and including a bearing sup- port for the impeller shaft and having a 70 plurality of guide vanes arranged in the annular channel above the impeller, forming 75 reversing channels to receive the water as delivered by one impeller, reverse the di- 80 rection of flow of the stream, and guide the 85 same into the next impeller above.

The accompanying drawings illustrate an 90 embodiment of my invention, and referring 95 thereto:

Fig. 1 is a vertical transverse section of 100 two stages of my pump, the upper bowl be- 105 ing part in elevation and part in section. The lower part shows an elevation develop- 110 ment of the impeller in the turbine bowl 115 chamber and also the guide vane reversing 120 channels. Fig. 2 is a bottom plane of the 125 impeller. Fig. 3 is a sectional elevation of 130 a portion of the turbine bowl, showing the 135 funnel shaped impeller chamber and the 140 guide vane reversing channels.

Similar numerals refer to similar parts 145 throughout the several views. The pre- 150 ferred embodiment of my invention as illus- 155 trated in the drawings and as previously 160 set forth, consists essentially in a conical 165 impeller of the open vane type with helically 170 curved vanes operatively mounted with- 175 in a turbine casing bowl adapted to encase 180 the same, and provided with reversing 185 channels for guiding the water stream from 190 one impeller to the next one above. In Fig. 1, 1 is the suction end bearing bowl, carry- 195 ing suction pipe 25, and the lower bearing 200 6^a connected with the wall of the bowl by 205 webs 29. The intermediate turbine bowl 2 210 and the discharge end turbine bowl 3 may 215 be either screwed (as shown) or bolted to- 220 gether into as many stages as required for 225 the total lift which the pump may be re- 230 quired to operate against. Each stage bowl 235 is provided with an impeller 4 which is 240 operatively mounted on the pump shaft 5 and 245 fastened thereto by pin 16 within the tur- 250 bine bowl, each bowl providing a bearing 255 support 6, for journaling said shaft.

The impeller 4 is formed of open vanes 260 7, helically curved and carried on the frus- 265 tum of an inverted cone 8, said vanes being 270 twisted or warped so that they project out- 275 wardly at an angle of approximately 90 de- 280 grees (see 9, 9, Fig. 2) to the surface of the 285

cone 8, at any point of intersection therewith. That is to say, any line drawn across the upper working surface of the impeller vane at a right angle to the basal edge of the same will also be at a right angle to the surface of the hub or conical frustum at the point which it intersects the hub. The vanes are each, furthermore, disposed on the surface of the hub along such a line as would be generated by a point moving from the center of a rotating disk to the edge of the disk, the speed of the disk and the point being equal. The outer edges 10, of the vanes conform to the outline of an inverted cone 14, forming a close running fit with the turbine bowl upper end of funnel shaped clearance ring 27 as at 11. There is thus formed a water path 21, 22, of greater area at the discharge end 12, than at the suction end 13, thus utilizing the centrifugal force of the water as the impeller revolves under speed while the upwardly pitched vanes 7, elevate the water causing it to flow with minimum shock.

When the impeller 4 is revolving in turbine bowl 2 or 3, the outer edges 10, of the vanes 7 form a close running fit with the funnel shaped portion or impeller chamber 27 of the bowl at 11, constituting a seal and preventing leakage. The angle of inclination of the edges 10 of the impeller, likewise the angle of inclination of the funnel shaped portion 11 of the impeller chamber 27, as indicated by A (see 15, Fig. 1), and the angle of inclination of the conical surface of the hub 8, may be any suitable angle between 5 degrees and 85 degrees with relation to the perpendicular axis 5, according to the desired effect. The surface line defining the inclination of the seat and the edge of the vane is straight, as shown in Fig. 1, thereby minimizing frictional resistance to the flow of the water over the said surface.

The turbine bowls 1, 2 are each formed with a funnel shaped chambered portion 27 at its upper end adapted to incase an impeller, the impeller cone 8, and vane tips being of a larger diameter at the upper discharge end 12 than at the lower suction end 13. The lower end of the funnelled wall 11 forms a narrow neck 28, defining the suction entrance to the impeller and taking the place of the ordinary shroud and suction neck. Above the respective impellers 4 the bowls 2, 3, are provided each with an annular water channel 19, formed around the conical bearing hub 20 and extending from the discharge end 12 of one impeller up to the suction end 13 of the next impeller above. Within each channel a plurality of guide vanes 18 are radially disposed and positioned with their lower ends 24 inclined at the proper angle (see Fig. 1) to receive the water delivered by the

impeller tips 12, these guide vanes reversing the direction of flow of the water and guiding the same into the next impeller above at the proper angle to enter between the vane tips 13.

This type of deep well pump is suspended in the well, submerged at the bottom of the discharge column 26, which is connected to the discharge head at the surface of the ground. A vertical drive shaft 5, spinning in the center of said column and journaled at intervals, transmits rotative power to the pump impellers 4, 4, below. The water entering the suction pipe 25 is picked up by the first impeller 4, which imparts a certain head to it and delivers it through the guide vane channels 19, 19 on to the next impeller 4, which imparts an additional head and so on through as many stages as required for the lift. Means for vertical adjustment of the impellers 4, 4, within the bowls 2, 3 is provided for by a threaded nut on the head shaft in the discharge head of pump at the surface of the ground (not shown). The vanes 19 have both ends directed toward the same side of the pump so that the circumferential direction of flow of water leaving these vanes is reversed relative to the circumferential direction of flow when entering between the vanes. The water is, consequently, received by the impeller vanes above the guide vanes on planes substantially parallel with the working faces of said impeller vanes so that whirling of the water as it passes from the guide vanes to the impeller is practically eliminated and there is no loss of efficiency due to formation of whirls.

It will of course be understood that various changes in construction may be made at any time if desired, within the scope of the appended claims, without in the slightest degree departing from the spirit of my invention, the drawings and description thereof herein contained, illustrating and explaining merely the preferred embodiment of my invention such as constitutes a disclosure of the principle involved.

Having thus described the invention what I claim as new and desire to secure by Letters Patent, is—

A deep well turbine pump including a casing bowl having an annular funnel-shaped inner wall portion at its upper end, a second bowl secured upon the first bowl in axial alinement therewith and having its inner wall tapering upwardly and terminating in an annular funnel-shaped portion similar to the first-mentioned funnel-shaped wall, conical impellers of the open vane type operatively mounted with relation to the respective funnel-shaped wall portions and each including a plurality of helically curved vanes and an impeller hub of greater diameter at its upper end than at its lower

end, the vanes being disposed at an angle of ninety degrees to the surface of the hub at all points of intersection therewith, the outer lower edges of said vanes conforming to the outline of an inverted cone and operating in a close running fit with the funnel-shaped wall portion of the respective bowl, a conical hub between the impellers, the space between said hub and the upwardly tapering wall of the second bowl constituting an annular water path estab-

lishing communication between the impellers, and a plurality of spiral guide vanes positioned in said path, said guide vanes having their opposite ends directed toward the same side of the casing bowl whereby to reverse the direction of flow of the water and extending from the discharge end of one impeller to the suction end of the next impeller above.

July 9th, 1923.

IMMANUEL ALVIN OLIVER.
